UNITED STATES PATENT OFFICE.

SEWARD CHARLES, OF WASHINGTON, DISTRICT OF COLUMBIA.

REINFORCED CONCRETE STRUCTURE.

1,382,060.

Specification of Letters Patent. Patented June 21, 1921.

Application filed March 26, 1918. Serial No. 224,825.

To all whom it may concern:

Be it known that I, SEWARD CHARLES, a citizen of the United States, residing at Washington, in the District of Columbia, have invented certain new and useful Improvements in Reinforced Concrete Structures; and I do hereby declare the following to be a full, clear, and exact description of the invention, such as will enable others skilled in the art to which it appertains to make and use the same.

My invention relates to concrete structures in general and to means for producing the same, but has reference more particularly to novel and improved means for reinforcing such concrete structures, and for accurately spacing and retaining their reinforcing elements in position during the process of pouring, shaping or otherwise forming the completed structure.

This invention has for an object the production of monolithic reinforced concrete structures characterized by an unusual degree of strength, rigidity and durability, as compared with their extreme light weight.

The invention also provides for, and makes possible the rapid production of such monolithic concrete structures with great accuracy and precision; and, while equally applicable to the construction of buildings, bridges, culverts, conduits, storm sewers, aqueducts, subways, tunnels and like structures of reinforced concrete or other suitable moldable material, the present invention is primarily designed and adapted for the manufacture of sea-going vessels. In this latter use, therefore, by way of exemplification, the invention will now be particularly described and thereafter pointed out by the appended claims.

In the accompanying drawings which form part of this application for Letters Patent, and whereupon like reference characters indicate corresponding parts in the several views:

Figure 1 is a longitudinal vertical central sectional view illustrating, diagrammatically my invention as applied to the hull of a concrete vessel.

Fig. 2 is a fragmentary view showing in horizontal section the bow of a concrete vessel below its main deck.

Fig. 3 is a view corresponding with Fig. 2, but taken at the opposite end or stern of a vessel.

Fig. 4 is a vertical diagrammatic section

taken transversely through the entire structure.

Fig. 5 is a fragmentary detail view, showing in perspective my improved double reinforcing elements, and means for accurately spacing the same.

Fig. 6 is a fragmentary detail view taken transversely through either the hull, decks, or partitions of a vessel, and

Fig. 7 is also a fragmentary view of one reinforcing bar in side elevation, broken away to expose an attaching eye or loop formed therein.

Reference being had to the drawings and numerals thereon, 1 indicates the hull of a vessel, and 2, 2 horizontal decks thereof, the same being intersected by longitudinal partitions 3, and by transverse partitions 4 at frequent intervals, as shown by Figs. 1-4, thus serving as bulkheads to divide the entire vessel into a multiplicity of individual cells or compartments 5.

These compartments may be independent, or may be made to communicate as shown, by agency of through ports or openings 6 in said longitudinal partitions 3, and by openings such as 7 in the transverse partitions 4. They may or may not be provided with doors or suitable closures (not shown), but are preferably of substantially circular form for the aforesaid purpose of establishing communication between adjacent compartments, and also for reducing weight without materially weakening their respective partitions.

The reinforcing means employed throughout the hull, decks, partitions, and the entire unitary construction of a vessel, include a double series of vertical and horizontally arranged flexible metallic bars 8 and 9 respectively, preferably of flat merchant iron and of suitable cross sectional area, as best shown by Fig. 5 of the drawings. These bars 8 and 9 are all deformed at suitable and regular intervals by eyes 10 punched out of the bars themselves, as best shown by Figs. 5 and 7, and for purposes later to appear.

In structural arrangement all bars 8 are crossed by bars 9, with one series of said eyes 10 equidistant from each point of intersection, and also oppositely disposed with relation to another series of eyes 10 similarly formed upon a duplicate set of crossed bars 8 and 9, as will be seen by reference to Figs. 5 and 6. By these figures also it will

be observed that the aforesaid duplicate sets of reinforcing bars 8 and 9 are in turn spaced apart and connected by stirrups 11 of relatively stiff wire or rod iron, terminating 5 at both ends in corresponding arcs 12. It will also be seen that these arcs 12 are positioned in parallel planes at right angles to that occupied by their respective rods or stirrups 11, and that each passes completely 10 through one series of eyes 10 upon their respective intersecting bars 8 and 9 of each set, thereby accurately spacing the aforesaid oppositely disposed sets of reinforcing bars, and effectually guarding against any dis- 15 placement thereof during the process of pouring or otherwise applying concrete to the double metallic skeleton thus produced.

To this skeleton frame is applied suitable concrete by any suitable means, and of suitable consistency, although experience has shown that a relatively dry mixture of concrete possesses a greater compressive strength than concrete applied in a semi-liquid condition. Such a mixture is therefore preferred, and, as shown by Fig. 6, an additional element 13 may, when desired, be added outside of each set of bars 8-9, near opposite sides of the walls of the structure, this element 13 comprising a permanent 20 metal fabric of relatively small mesh in large sheets, being inwardly looped upon itself at frequent intervals at 14 as a means of uniformly offsetting the sheets 13 from their adjacent reinforcing bars 8 and 9 to 25 which they are wired as shown at 15, Fig. 6. By this means a uniform deposit of concrete 30 outside of the reinforcing bars 8 and 9 is insured upon both sides of the structure, the said reinforcing bars being thus uniformly 35 embedded and protected from the action of water, the screen 13 serving also to confine the reasonably dry concrete, and to assist 40 when desired in shaping or forming the structure.

Finally, an outside finish 16 of any suitable waterproof material is troweled upon, or otherwise applied to, the oppositely disposed screens 13, before the main body of concrete 17 has taken its initial set, the concrete body 17 and outer finishing surface 16 being securely bonded together through the meshes of said screens 13 to complete the structure.

When applied thus to the production of 55 unitary hulls for vessels, it will be observed that a remarkably staunch and rigid structure is produced, based upon a combined arch and beam theory of construction, so

that forces exerted upon the shell or hull of the vessel, are in part carried by the arch 60 structure thereof, and partly by the transverse partitions 4 serving as beams between its transverse walls, while at the same time the partitions 3, the decks 2, 2, the sides, and keelson of the vessel constitute a most effective system of longitudinal braces. 65

Having thus described an embodiment of my invention, it should be understood that same is not confined for its patentable novelty to the precise structural arrangement 70 and combination of parts shown and described, nor yet to the proportion of parts, the material or materials indicated, nor the article produced. Neither am I limited nor restricted to any particular method of pouring 75 or shaping concrete structures, since any known form or manner of construction may be employed without departing from the spirit of my invention.

What I do claim, however, and now desire 80 to secure by Letters Patent is:

1. A concrete structure having reinforcing elements embedded therein including in combination oppositely disposed series of intersecting metallic bars, and arcs of relatively 85 stiff wire interwoven with said bars to secure them together at their points of intersection.

2. A concrete structure having reinforcing elements embedded therein including in combination oppositely disposed series of intersecting metallic bars, eyes formed upon said bars, and arcs of relatively stiff wire interwoven through said eyes to secure the bars aforesaid together at their points of intersection. 90

3. A concrete structure having embedded 95 therein oppositely disposed series of intersecting reinforcing bars, in combination with interposed stirrups, each of said stirrups arranged and adapted to connect the bars of each series and to space one series of said bars from the other. 100

4. A concrete structure having embedded near each outer face thereof a series of intersecting reinforcing bars, in combination with stirrups terminating at each end in arcs adapted to connect the bars of each series and to space one series of said bars from the other. 105

In testimony whereof I affix my signature, 110 in presence of two subscribing witnesses.

SEWARD CHARLES.
